AUTOMATIC CHAIN LUBRICATOR

Marlin C. Moore, Milwaukee, Wis.

Application June 26, 1957, Serial No. 668,159

10 Claims. (Cl. 184—15)

This invention relates to chain lubricators, and more particularly to an air operated device for automatically lubricating the individual chain links of an overhead conveyor.

It is manifest to anyone familiar with the art, that in the lubrication of the chain links in an overhead conveyor, and more particularly where the link pins are in a vertical position, that due to intervening trolley brackets depending from the chain, it is impossible to have oil dispensing nozzles placed in a fixed position over the chain. The principal object of my invention is to provide a device having means for automatically moving oil dispensing nozzles in and out of precise lubricating position over the pivot pins during movement of the conveyor.

Another object of my invention is to provide a lubricating device adaptable for conveyor chains, which may cooperate automatically with the trolley hangers or similar attachments on the chain to cause oil dispensing nozzles to be moved out of lubricating position relative to the conveyor chain pivot pins, after certain of said pins have been lubricated.

Another object of my invention is to provide a device having means for swinging the entire lubricating unit out of position, to permit the carriage or parts suspended therefrom to pass a given point, but permitting restoration of the unit with its dispensing nozzles in the proper position for supplying metered amounts of lubricant to the individual pivot pins during predetermined cycles of operation of the conveyor or chain.

Other objects of my invention will become more apparent as the description proceeds when taken in conjunction with the drawings, in which:

Figure 1 is a top or plan view of a conveyor structure to which a lubricating device made in accordance with the invention is applied, but with certain parts broken away to show details of the conveyor;

Figure 2 is a sectional view of the device shown in Figure 1, taken on the lines 2—2 of Figure 1 and illustrating the manner in which the lubricating device may be swung into or out of lubricating position relative to the conveyor;

Figure 3 is a diagrammatic view of the principal parts of the lubricating system;

Figure 4 is a detail view of the master valve;

Figure 5 is an enlarged longitudinal section of the oil dispensing distributor; and

Figure 6 is an enlarged detail section taken on line 6—6 of Figure 1.

Referring now to details of the illustrative embodiment of the invention shown in the drawings, the character 10 indicates an I-beam which forms the main support for a chain conveyor 16. Said I-beam has a rigid frame 11 on its upper face, consisting of end pieces 12 and 12', connected by a side member 13, and having a plate 14 near one end thereof. A lubricator unit 15 is hinged at 19 and 19' to one side of the frame 11 along one side of the I-beam, and includes two end pieces 16, 16'; a depending

plate 17; and a lower platform 18 forming the frame for said unit. This lubricator unit 15 has upwardly extending brackets 21 and 21' at opposite ends, opposed to upstanding brackets 20, 20' on the end pieces 12, 12' of the fixed frame 11. Tension springs 22 and 22' connect the brackets 20, 21 and 20', 21', respectively, so as to tend to swing the lubricator unit 15 into a partially raised position away from the conveyor chain 26, as shown by dotted lines in Figure 2, when the lubricating unit is not in use.

The rail 10 serves as a support for a plurality of spaced carriages or yokes 23, which have opposed rollers 24, rotatably mounted on horizontal pins 25 at opposite sides of the I-beam, so as to permit the carriages to move laterally along the rail 10. The carriages 23 are connected by the conveyor chain 26 at spaced points below the I-beam. Said conveyor chain consists of a plurality of links 26 joined by upright pivot pins 27. The conveyor may have any suitable supporting devices (not shown) connected thereto for conveying material. The side member 13 of the rigid frame 11 may have a plurality of depending brackets 28, which support rollers 29 on vertical pins 30 at their lower ends. These rollers 29 serve as lateral supports for one side of the conveyor chain 26.

The lower platform 18 of the lubricator unit 15 has a pair of sprockets 32 and 32' rotatably mounted thereon by upright pivot pins 33, 33'. The sprockets 32 and 32' have an auxiliary chain 34 trained thereabout, which has a plurality of rollers 35 on brackets 35' projecting outwardly therefrom so that one reach of said auxiliary chain is adapted for driving inter-engagement with certain links of the conveyor chain 26, thus causing said auxiliary chain to move in an orbital path as shown by the arrow in Figure 1. The sprockets 32 and 32' are provided with upwardly extending pins 36 on equal radii, which are connected by a bar 37. As the sprockets 32 and 32' revolve, the bar 37 oscillates in a cycloidal path, as indicated by the dotted lines in the same figure. In the form shown herein, the bar 37 has a depending flange 37'.

A master air valve 38 is mounted on the frame, and is connected by a flexible tube 41 to an air cylinder 42 on frame 11 provided with a plunger 43 which is adapted to engage an outwardly extending member 20" of the bracket 20 mounted on the end member 16 of the hinged lubricator frame 15. Valve 38 may be suspended from plate 14 or otherwise supported from the frame in the position illustrated in Figures 1 and 2. Since the details of supporting the valve 38 in the position illustrated form no part of the present invention, the valve is illustrated diagrammatically, without a showing of its supporting connection. Air pressure is supplied to the valve 38 by an air supply duct 44. A flexible tube 45, common with the tube 41, leads from the valve 38 to an air valve 46 fixed on the platform 18 (see Figure 6). Said air valve 46 is operated by a lever 47 having a roller 48 at its outer end adapted to be contacted by the flange 37' of oscillating bar 37 on the sprockets 32, 32'. This air valve 46 has a duct 49 which leads to an oil distributor 50 mounted on the vertical wall 17 of the lubricating frame 15. This distributor 50 has an air cylinder 51 with spring-pressed piston 51' and piston rod 51" therein. Said piston rod is connected to an oil metering device 52 which is of a well-known commercial form, including a plunger 52' movable along a cylinder 52" to supply metered amounts of oil to a plurality of tubes 53, 53 each leading to oil dispensing nozzles 53', 53''. Oil is fed to the dispensing cylinder 52" from an oil reservoir 55 mounted on the plate 14 through a flexible tube 54. The plunger 52' has a central bore 55 and a cross bore 56 communicating with its outer end. The arrangement is such that upon

outward movement of the plunger 52' a precise amount of oil will be successively discharged through each of the tubes 53 and their respective oil nozzles 53'. All of the nozzles 53' are fixed on the bar 37 to oscillate toward and away from the conveyor chain 26.

The air valve 38 is of a conventional three-way type being movable into an on, or a combined off and exhaust position, by a control arm 39. Said control arm has a depending lug 39' at its outer end, in position to be engaged by a trip arm 23' projecting from one of the conveyor carriages 23, as will hereinafter be more fully described.

By referring to Figure 2, it will be noted that the entire lubricating unit is hingedly supported at 19, and is normally held by springs 22 in a retracted position, shown by dotted lines, so that the entire unit is swung away from the chain 26, in an out-of-the-way position, so that it cannot interfere with the operation of the conveyor.

The use and operation are as follows:

When it is desired to lubricate the chain 26, the handle 39 is manipulated to open the air valve 38. Air under pressure supplied through tube 44 passes through said air valve and divides into two directions—one through tube 41 to extend plunger 43 of the cylinder 42, so as to force the angle plate 20 outwardly, thus swinging the entire lubricating unit inwardly to its full-line, lubricating position shown in Figure 2.

Air from the valve 38 also passes through the flexible tube 45 to the valve 46. The opening of this valve is controlled by a spring-pressed arm 47, which has a roller 48 at its outer end adapted to be engaged by the flange 37' on bar 37 to swing the arm 47 to its open position only when said bar is moved to its innermost position relative to the conveyor, as seen in Figures 1 and 3.

The bar 37 connecting the sprockets 32 and 32' is so rotated in timed relation to the movement of the conveyor chain 26 that the valve 46 will only be opened when the four oil nozzles 53' shown in Figure 1 are disposed immediately above the same number of pivot pins 27 of the conveyor chain 26, as seen in Figure 1.

Opening of the air valve 46 causes air under pressure to be conducted through tube 49 to the air cylinder 50, which actuates the oil metering device 52, thereby causing a small amount of oil to be discharged through each of the dispensing tubes 53 and their respective oil nozzles 53'. Thus, a few drops of oil will be distributed by pressure directly on the upper ends of those pivot pins which are at that instant disposed below said nozzles.

As the conveyor chain is moving in the direction of the arrow in Figure 1, the auxiliary chain 34 will also be moved along with said conveyor chain in the same direction, so that the connecting bar 37 will quickly move away to permit air valve 46 to be closed by its spring, and also cause the nozzles 53' to be withdrawn laterally from above the chain 26. Closing of this air valve will also relieve pressure in the air cylinder 50, so that the oil dispensing device 52 will be restored to an initial position ready for the next oiling cycle.

It will be further understood that the auxiliary chain 34 is orbitably movable in such timed relation with the conveyor chain 26, that the next time the connecting bar 37 reaches its uppermost position so as to open air valve 46 for dispensing another "shot" of oil, the next four succeeding pivot pins 27 of the conveyor chain 26 will have been progressed into a position where the four dispensing nozzles 53' will be simultaneously moved inwardly on bar 37 into registering position over said pins. In this manner, repeated oiling operations on successive groups of chain pins can be continued until the entire chain is lubricated. Operation of the lubricating system may, however, be discontinued at any time by manually moving the valve arm 39 to its closed position, or it may be automatically discontinued by engagement of the trip arm 23' on one of carriages 23 of the conveyor chain 26 (see Figure 2), so the master valve 38 will be

closed after all of the chain pins of said conveyor chain have been oiled.

When the master valve 38 is closed, air pressure will simultaneously be relieved from the air cylinder 42, so as to permit the lubricating assembly 15 to be swung by springs 22 into an out-of-the-way position relative to the conveyor chain, as shown in dotted lines in Figure 2.

From the above description, it will now be understood that my improved form of air operated lubricator is driven by the conveyor chain so as to actuate a group of oil dispensing nozzles which move in and out over the conveyor chain as well as along with it, without interference with the trolley brackets. The nozzles are properly positioned over the chain pins so as to dispense an accurately metered amount of oil on the top of each pin.

The assembly frame holding the moving parts of the lubricator is suspended on pivots. Shutting off the air to the air cylinder 42 causes the unit to disengage and be completely inactive. This shutoff may be accomplished either manually, or automatically by a tripping member attached to a trolley hanger or bracket. The automatic shutoff not only causes the lubricator unit to be swung away from the conveyor but discontinues operation of the lubricator means after the conveyor chain has completed one circuit and all pins have been lubricated.

The occasional use of the lubricator will assure all chain pins being uniformly and adequately lubricated without any manual labor. This will result in decreased wear and maintenance and less load on the drives.

Although I have shown and described certain embodiments of my invention, it will be understood that I do not wish to be limited to the exact construction shown and described but that various changes and modifications may be made without departing from the spirit and scope of the invention as defined by the appended claims.

I claim:

1. A lubricating device for conveyor chains having links connected by pivot pins, comprising an oil metering device, a plurality of nozzles fed from said oil metering device, means for supporting said nozzles in spaced relation along said conveyor chain the same distance as the distance between adjacent pivot pins, means for actuating said oil metering device, and control means interengaged and movable with said conveyor chain for operating said actuating device momentarily when said nozzles are in oil-depositing registry with a plurality of said pivot pins.

2. The structure of claim 1, wherein the oil metering device and the actuating and control means therefor are mounted on a frame movable into and out of cooperative relation with the conveyor chain.

3. The structure of claim 2, wherein fluid pressure means is provided for moving the frame and for actuating the oil metering device, and control means is provided for said fluid pressure means for rendering the oil metering device inoperable when the frame is moved out of cooperative position relative to the conveyor chain.

4. The structure of claim 3, wherein the supporting means for the nozzles is actuated by said first named control means for movement into and out of registering position with adjacent pivot pins.

5. In combination with a conveyor chain having links connected by pivot pins, a supporting frame for said conveyor chain, a lubricating unit for said pivot pins hinged on said frame for movement toward and away from said conveyor chain, said lubricating unit comprising a plurality of nozzles adapted to be moved with said unit into simultaneous registering oil dispensing relation with a plurality of successive pivot pins on said conveyor chain, and means operable in timed relation with the movement of said conveyor chain for dis-

pensing a predetermined amount of oil to said nozzles when said nozzles are in simultaneous registering relation with a plurality of pivot pins.

6. The structure of claim 5, wherein the means operable in timed relation with the movement of the conveyor chain includes means for simultaneously withdrawing said nozzles and discontinuing the supply of oil to said nozzles.

7. The structure of claim 5, wherein tension means is provided for normally swinging said lubricating unit away from said conveyor chain, and fluid pressure means is provided for swinging said unit into operating position relative to said frame, and additional fluid pressure means actuate the oil dispensing means.

8. The structure of claim 5, wherein the means operable in timed relation with the movement of the conveyor chain includes a rotatable member mounted on the swingable lubricating unit and actuated in response to movement of the links of the conveyor chain, and the first named means also includes a control valve operated when the member has rotated through a circumferential distance corresponding to the distance between the predetermined number of pivot pins of the conveyor chain which are served at one time by the nozzles of the lubricating unit.

9. In combination with a conveyor chain having links connected by pivot pins, a supporting frame for said

conveyor chain, a lubricating unit for said pivot pins including a pair of chain sprockets mounted adjacent said conveyor chain and having an auxiliary chain trained thereabout, one reach of said auxiliary chain having driving interengagement with said conveyor chain, a bar connecting said sprockets so as to be oscillated in an orbital path toward and away from said conveyor chain, an oil dispensing nozzle mounted on and movable with said bar, and means actuated in timed relation with said auxiliary chain for discharging oil through said nozzle when the latter is in registering position with one of the pivot pins of said conveyor chain.

10. The structure of claim 9, wherein a plurality of oil discharging nozzles are disposed along the bar in spaced relation so as to be movable simultaneously into and out of registering position with a plurality of pivot pins of the conveyor chain.
